UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,808, dated May 16, 1899.

Application filed April 6, 1899. Serial No. 712,022. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part 5 thereof, in which—

Figure 1 is a top or plan view of a manhole-cover embodying my design, and Fig. 2 is a cross-sectional view of Fig. 1.

The views are deemed necessary or essential 15 for the proper illustration and understanding of the design of my invention.

The leading feature of my present design consists of the configuration or outline, as well 20 as the surface ornamentation, of the manhole-cover.

Referring to the drawings, the cover when viewed in plan presents the appearance of a circular field *a* inclosed within two concentrically-arranged rings or annular rims *b* and *d*, 25 the inner ring *d* being rounded or curved on its uppersurface, while the outer ring *b* is flat, or substantially so. Within the field *a* and at points radiating from the center of the field are grouped a series of ring-shaped ornaments 30 *f*, the upper faces of which are flat, or sub-

stantially so. When viewed in cross-section, the cover is substantially dish-shaped and has a base *g*, which is inwardly bulged or convexly arranged, as at *g'*, toward the center of the field *a*. The rim of the cover, which terminates at the top in the outer ring *b* of the field *a*, is offset and rounded, as at *h*, to form the inner ring *d*, surrounding the field *a*. The ring *d*, therefore, is below the ring *b*. The convex base *g* of the cover rises in the form of 40 an arch from an annular ring *k*, depending below the base at the periphery or rim of the cover, and the point of junction of the ring *k* with the base *g* is rounded, as at *k'*. From the base *g* projects a series of tubes *m*, the upper faces of which form the ring-shaped ornaments *f* of the cover. 45

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.
